(57) **CLAIM**

The ornamental design for a pajamas with zipper, as shown and described.

DESCRIPTION

FIG. 1 is a perspective view of the pajamas with zipper, showing the new design;

FIG. 2 is a front elevational view of the pajamas with zipper thereof;

FIG. 3 is a rear elevational view of the pajamas with zipper thereof;

FIG. 4 is a left side elevational view of the pajamas with zipper thereof;

FIG. 5 is a right side elevational view of the pajamas with zipper thereof;

FIG. 6 is a top plan view of the pajamas with zipper thereof; and,

FIG. 7 is a bottom plan view of the pajamas with zipper thereof.

The broken lines shown illustrate portions of the pajamas with zipper that form no part of the claimed design.
